United States Patent Office

Des. 186,034
Patented Sept. 1, 1959

186,034

SKI CAR TOY

Thomas G. Haines, St. Louis, Mo.

Application January 12, 1959, Serial No. 54,146

Term of patent 3½ years

(Cl. D34—15)

FIG. 1

FIG. 2

FIG. 3

Figure 1 is a perspective view of my design for a ski car toy;

Fig. 2 is a side elevational view thereof; and

Fig. 3 is a rear end elevational view.

The essential features of my design reside in those portions shown in full lines.

I claim:

The ornamental design for a ski car toy, substantially as shown and described.
